(57) **CLAIM**

We claim the ornamental design for wall interface for mounting device, as shown.

DESCRIPTION

FIG. 1 is a front elevation view of a wall interface for mounting device according to an embodiment of the invention;

FIG. 2 is a side elevation view of the wall interface for mounting device depicted in FIG. 1;

FIG. 3 is a top plan view of the wall interface for mounting device depicted in FIG. 1; and,

FIG. 4 is a front elevation view of the wall interface for mounting device depicted in FIG. 1.
